CONTACT

Douglas T. Mitchell, Westchester County, N. Y.

Application June 1, 1940, Serial No. 338,307

1 Claim. (Cl. 173—328)

My invention relates to contacts for radio hardware such as tube sockets, plug contacts, etc.

The object of the invention is to provide a contact which will permit its assembling on a single piece of insulation when used either for sockets or in alignment, thereby dispensing with a second piece of insulation commonly used in contact arrangements of this type. In addition, by using a single insulated piece in place of a double the assembling of a series of contacts is greatly simplified.

Another object of the invention is to provide a contact having a high frictional engagement with the bar or prongs for which it is made, thereby reducing the side sway of the bar in the insulation while the contact maintains a firm grip on the bar or prong engaged therein.

In the appended drawing forming part of this application,

Figure 1 is a vertical section on line 1—1, Figure 2,

Figure 2 is a side elevation of the contact as it appears mounted,

Figure 3 is a top view on a series of aligned contacts mounted on an insulated base, one of the contacts being shown in section on line 3—3, Figure 1.

Figure 4 is a section similar to that of Figure 1 of a contact showing a modified structure, and Figure 5 is a section on line 5—5, Figure 4.

Referring to the drawing the contact proper is formed of a single member, the middle part of which is shaped into a circular loop 7, the remainder of the member being shaped into a loop 8 of rectangular cross section, the end portions 10 of the member overlapping within the rectangular loop 8 preferably opposite the gap 9 which is common to both loops 7 and 8. The overlapping end portions 10 are perforated to accommodate an eyelet 11 by means of which the contact is secured to an insulation member 12 which may be used for a series of aligning contacts as shown in Figure 3, or the single insulation member may be shaped to receive contacts to form a lamp socket not shown.

The rectangular loop extends laterally to each side of the circular loop to provide shoulder 17, running substantially at right angles to the central plane of the contact. The formation of the shoulder 17 provides a greater stability to the contact when it is mounted and reduces side sway of a prong that is engaged by the contact formed of the two loops referred to.

The inside diameter of the eyelet 11 is slightly larger than the bar or prong which is to engage the contact in the gap 9 wherein a recess 13 is formed in each side of the gap to frictionally engage the bar or prong which may be passed into the contact through the eyelet 11.

The loops 7 and 8 at their junction 9 which is the common gap of the two loops forms the yielding means which provide the grip insuring a good contact between the recesses 13 formed in the sides of the gap and the bar forced into the said recesses after passing through the eyelet. To increase the resiliency of the loop 7 a flap 14 is cut out from the peripheral body of the loop opposite the gap. This flap in addition serves as means for attaching a contact thereto, and for that purpose an aperture 15 is provided in the flap 14.

In the modified form shown in Figures 4 and 5 the rectangular loop 8' is provided with yielding tongues 16 extending from the gap sides into the loop 8'. Said tongues are cut out from the sides of the rectangular loop 8' adjacent to the sides of gap 9', and the said tongues are bent and shaped to be in alignment with the corresponding recesses 13' formed in the sides of the gap 9'.

As will be seen from the drawing the rectangular loop 8 provides sufficient rigidity without sacrificing resiliency at the point of contact which results from the resiliency of the common gap of both loops 7 and 8.

In the modified form the resiliency at the point of contact is increased by the formation of the tongues without sacrificing the rigidity resulting from the formation of the rectangular loop in addition to the circular loop.

I claim:

40 In combination, an insulated member and a contact formed of a single member providing a circular loop and a rectangular loop, both loops being spaced by a common gap, the rectangular loop extending laterally to each side of the circular loop to provide shoulders running substantially at right angles to the plane of the contact, said rectangular loop having an opening opposite the gap, an eyelet securing the contact through the opening of the insulated member, the sides of the gap having recesses disposed cooperatively to the opening in the rectangular loop for permitting a member passing through the eyelet to engage the recesses in the gap of the loops.

DOUGLAS T. MITCHELL,
